US00D874429S

(12) **United States Design Patent** (10) **Patent No.:** **US D874,429 S**
(45) **Date of Patent:** **** Feb. 4, 2020**

(54) **HEADPHONES**

(71) Applicant: **Apple Inc.**, Cupertino, CA (US)

(72) Inventors: **Shota Aoyagi**, San Francisco, CA (US); **Robert Boyd**, Los Angeles, CA (US); **Robert Brunner**, San Francisco, CA (US); **Monica Fernandez**, Reseda, CA (US); **Christopher Kuh**, San Francisco, CA (US); **Christopher J. Stringer**, Woodside, CA (US)

(73) Assignee: **Apple Inc.**, Cupertino, CA (US)

(**) Term: **15 Years**

(21) Appl. No.: **29/667,339**

(22) Filed: **Oct. 19, 2018**

Related U.S. Application Data

(63) Continuation of application No. 29/622,980, filed on Oct. 20, 2017, now Pat. No. Des. 831,610, which is a continuation of application No. 29/575,696, filed on Aug. 26, 2016, now Pat. No. Des. 817,301.

(57) **CLAIM**

The ornamental design for headphones, as shown and described.

DESCRIPTION

FIG. 1 is a front perspective view of headphones showing the claimed design;

FIG. 2 is a front view thereof;

FIG. 3 is a rear view thereof;

FIG. 4 is a left side view thereof;

FIG. 5 is a right side view thereof;

FIG. 6 is a bottom view thereof; and,

FIG. 7 is a top view thereof.

The dashed broken lines in the figures show portions of the headphones that form no part of the claimed design

The dot-dash broken lines in the figures show boundaries that form no part of the claimed design.

1 Claim, 5 Drawing Sheets
